(57) **CLAIM**

The ornamental design for a teething toy, as shown and described.

DESCRIPTION

FIG. 1 is a front view of a teething toy;

FIG. 2 is a rear view of a teething toy;

FIG. 3 is a right side view of a teething toy;

FIG. 4 is a left side view of a teething toy;

FIG. 5 is a top plan view of a teething toy; and,

FIG. 6 is a bottom plan view of a teething toy.

The broken lines illustrate portions of the teething toy which form no part of the claimed design.
